UNITED STATES PATENT OFFICE.

ROBERT J. MULVEY, OF CHICAGO, ILLINOIS.

GARMENT FASTENER.

Application filed March 21, 1921. Serial No. 453,971.

To all whom it may concern:

Be it known that I, ROBERT J. MULVEY, a citizen of the United States, and a resident of the city of Chicago, county of Cook, 5 and State of Illinois, have invented certain new and useful Improvements in Garment Fasteners, of which the following is a specification.

My invention relates to improvements in 10 garment fasteners, more particularly to the ordinary snap fasteners, the object of the invention being to provide improved means for securing the same in place.

Other objects will appear hereinafter.

15 The invention consists in the combinations and arrangements of parts hereinafter described and claimed.

The invention will be best understood by reference to the accompanying drawings 20 forming a part of this specification, and in which,

Fig. 1 is a plan view of a fastener embodying the invention;

Fig. 2, a section taken on line 2—2 of the 25 same; and

Fig. 3, a section taken on line 3—3 of the same.

The preferred form of construction as 30 illustrated in the drawings comprises a sheet metal disk 4 having a central recess or well 5 therein provided with slots 6 on the opposite sides thereof. The disk 4 is provided around its edges with a backwardly turned securing flange 7 and a fastening

35 element 8 is arranged thereunder as shown. The fastening element 8 is in the form of a spring wire bent into substantially U-shape with a body thereof arranged under the flange 7 and with the ends thereof positioned in the slots 6 and whereby said ends constitute snap fastenings for securing the ordinary headed stud in the well or recess 5 as will be readily understood by those skilled in the art.

40 The construction already described forms, in itself, no part of the present invention, the same constituting the subject matter of my co-pending application filed July 24, 1920, Serial No. 398,691.

45 As a means for securing the fastening element already described in place on a garment, I provide a securing element in the form of a spring wire tortuously bent as shown to provide a curved portion 9 under-

55 in place by means of a hook 10 formed on the extreme secured end of said wire and engaging the loop or bend 11 thereof as shown and whereby said wire will be securely and resiliently held in place on the 60 back of the fastener body. The free portion 12 of said wire is further tortuously bent and extended across the body of the disk 4. The extreme free end thereof is formed into a hook 13 adapted and arranged to engage under a loop 14 formed in the portion 9 of said wire and projecting outwardly from under the flange 7 as shown. By this arrangement a simple and effective means is provided for locking the free end 65 of the wire portion 12 in operative relation with the body of the fastener.

In use the fastener is secured in place upon the garment by threading the portion 12 of the wire securing element through the cloth 70 of the garment and then engaging the hook 13 with the loop 14 whereby the fastening element may be quickly and securely mounted in place without the use of stitches or the like. By this arrangement the fastening element will be securely and resiliently held in place and in flat relation with the 75 garment to which it is applied. The specific fastening element disclosed constitutes the female portion of the snap fastener 80 which, it is to be understood, co-operates with a suitable male member, not shown, and which may if desired be secured in place by similar means.

85 While I have illustrated and described the preferred form of construction for carrying my invention into effect, this is capable of variation and modification without departing from the spirit of the invention. I, therefore, do not wish to be limited to the 90 precise details of the construction set forth, but desire to avail myself of such variations and modifications as come within the 95 scope of the appended claims.

Having described my invention, what I 100 claim as new and desire to secure by Letters Patent, is:—

1. In a fastener, the combination with a disc having a socket therein and slots in the walls of said socket on opposite sides 105 thereon; a securing member associated with said disc, said securing member being tortuously bent across the back of said disc and having its opposite ends engaging said slots; and a fastening member associated with said 110

disc, said member being adapted to be threaded through the cloth of a garment for releasably fastening said fastener in position, there being a hook on each end of 5 said fastening member for holding said fastener in such position.

2. In a fastener, the combination with a disc having a socket therein and slots in the walls of said socket on opposite sides 10 thereon; a securing member associated with said disc, said securing member being tortuously bent across the back of said disc and having its opposite ends engaging said slots; and a fastening member associated 15 with said disc, said member being adapted to be threaded through the cloth of a garment for releasably fastening said fastener in position, and means at opposite ends of said fastening member for holding said 20 fastener in such position.

3. In a fastener, the combination with a disc having a backwardly turned securing flange; securing means tortuously bent across said disc; a resilient fastening member associated with said disc and arranged 25 under said flange for fastening said fastener to a garment; and means at opposite ends of said fastening member for holding said fastener in such position.

4. In a fastener, the combination of a disk having a securing flange; a fastening member therefor having one portion secured under said flange, the remainder of said member being tortuously bent across the said disk; a hook at one end of said member engaging said tortuously bent portion and a hook at the opposite end of said member en- 30 35

gaging a loop formed in said member for holding said member in such position under said flange, substantially as described. 40

5. In a fastener, the combination with a disc having a backwardly turned securing flange; securing means tortuously bent across said disc; a resilient fastening member associated with said disc and arranged 45 under said flange for fastening said fastener to a garment; a hook formed at one end of said fastening member and engaging a bent portion thereof; and a hook formed at the opposite end of said fastening member and 50 engaging a portion of the tortuously bent portion of said fastening member, said hooks being arranged and adapted to hold said fastener in such fastened position.

6. Means for fastening a fastener to a 55 garment, or the like, comprising a fastening member associated with and tortuously bent across the body of said fastener; said fastening member being adapted to be threaded through the cloth of the garment for fastening said fastener in position; and hook members at opposite ends of said fastening member and engaging portions of the tortuously bent portion of said fastening member for holding said fastener in such fastened position. 60 65

In testimony whereof I have signed my name to this specification in the presence of two subscribing witnesses.

ROBERT J. MULVEY.
